UNITED STATES PATENT OFFICE.

GEORGE S. DUFFIN, OF MILLERSBURG, INDIANA.

DRAFT-EQUALIZER.

1,258,755.

Specification of Letters Patent. Patented Mar. 12, 1918.

Application filed March 23, 1917. Serial No. 156,961.

To all whom it may concern:

Be it known that I, GEORGE S. DUFFIN, a citizen of the United States, residing at Millersburg, in the county of Elkhart and State of Indiana, have invented certain new and useful Improvements in Draft-Equalizers, of which the following is a specification.

This invention relates to draft equalizers, and is designed to be used as a connecting medium between an animal-drawn vehicle or machine and the animals which draw the vehicle or machine. The device may be considered an extension or continuation of or an improvement on the equalizer on which I was granted the Patent #1,040,174, issued Oct. 1st, 1912.

The primary object of the invention, therefore, is to provide certain improvements, not provided in said patent, and unknown to me prior to this invention. A further object is to provide a device of this character which will result in the maximum efficiency in utilizing and distributing the power exerted by the draft animals.

A further object of this invention is to provide a device of this character that is comparatively simple of construction, strong, durable, thoroughly practical, comparatively inexpensive and entirely automatic in its operation.

Various other objects and advantages will become apparent from an understanding of the following description.

These objects are attained by such means as are shown in their preferred form and environment in the accompanying drawings, described in the following description and particularly recited in the appended claims.

In the accompanying drawings wherein like characters designate like parts throughout the several views:—

Figure 1 is a view in perspective showing my invention as in its preferred embodiment;

Fig. 2 is a view in perspective of an improved connecting link that comprises part of my present invention;

Fig. 3 is a sectional view taken on line 3—3 of Fig. 1;

Fig. 4 is a view, in side elevation, of a portion of the device as shown in Fig. 1;

Fig. 5 is a top plan view of my invention as embodied in a modified form;

Fig. 6 is a sectional view taken on line 6—6 of Fig. 5; and

Fig. 7 is a sectional view taken on line 7—7 of Fig. 5.

In reducing my invention to practice, I provide the supporting structure or frame 10 of the horse-drawn vehicle or machine with spaced bearings 11 and 12, respectively, that are designed to support a movable rod, rock lever or reacting crank-shaft 13, which has its end portions bent in opposite directions and at right angles to its intermediate portion so as to form crank arms 14 and 15. The ends of the respective crank arms 14 and 15, may be formed into suitable eye portions 16 for connecting respectively with a bearing 17 and link 18 by means of pivots 19; the other end of the bearing being movably connected with the supporting structure 10, through the medium of a spacing member 20 and an eye-bolt 21; and the other end of the link 18 is pivotally connected to the lower arm of a vertically disposed lever 22 as at 23. The lever 22 is in turn pivotally mounted on the supporting structure or frame 10, as at 24, whereby said lever may be utilized in the capacity presently described.

As will be noted, upon referring to Fig. 4, the bearing 17 is cut out substantially intermediate its ends as at 25 to form an overhanging retaining shoulder 26 and to accommodate one end portion of a horizontal side-draft bar 27; a suitable fastening member 28 being passed through the shoulder 26 and the side-draft bar, as clearly shown in Fig. 1. The side-draft bar is horizontally disposed on a higher plane than the other equalizer members hereinafter mentioned. A link 29 has its intermediate portion passed through a suitable aperture in the upper end of the lever 22, as shown in Fig. 1, and has its respective eye portions 30 secured to the intermediate portion of the side-draft bar 27, as at 31, thereby co-operating with the arms 14 and 20 for adequately supporting the side-draft bar and

providing for movement thereof at certain times such as will presently appear.

Adjacent to its free end, the side-draft bar 27 may be provided with a suitable whiffletree (as in Fig. 5) to which one of the draft animals may be hitched in the usual manner.

From the foregoing, it will be seen that upon turning the crank-shaft or rod 13 and swinging the crank arm 14 and lever 22, the side-draft bar will be moved either forwardly or rearwardly, consistent with the direction of movement of the said arm and lever.

I further provide the supporting structure 10 with a hanger or bearing 32 which is fixed in place by a bolt 33. The support 32 carries a vertical lever 34, which is movable about its pivot 35. At its upper end, the vertical lever 34 is provided with an aperture 36 to receive a pivot or pin 37 which extends through the bifurcated end 38 of a link 39, as clearly shown in Fig. 1.

An inclined or diagonal lever 40 is pivotally supported on the supporting structure 10, through the medium of a bracket 41 (see Fig. 3). Said lever 40 has connection at one end with the link 39, by a pivot 42, and its other end extends through a receiving aperture or slot 43 of the horizontal connection link 18. Consequently, when sufficient forward pressure is applied to the lower end of the vertical lever 34, the same is moved about its pivot 35, so as to impart a rearward movement to the connected end of the inclined lever 40, through the medium of the link 39, and thereby cause forward movement of the link 18 and of the lower end of the lever 22 and turn the rod or crank shaft 13, and consequently effect rearward movement of the side-draft bar 27.

A clevis 44 is mounted on the lower end portion of the vertical lever 34, as shown in Fig. 1, and this clevis supports a double-tree 45 of ordinary construction. Equalizing levers 46 and 47 respectively are pivotally mounted, as at 48, upon the double tree 45, their outer ends carrying links 49 which in turn support the whiffletrees 50.

Adjacent their inner ends, the levers 46 and 47 are provided with longitudinal slots 51, which receive studs 52 of a yoke or V-shaped link 53, the latter carrying a link 54 for supporting another whiffletree 55.

As the principle involved in the three-horse evener or equalizing mechanism, represented by numerals 44 to 55 inclusive, is the same as that of my Patent #1,040,174, previously mentioned, I will omit a specific description of its operation, but will show how it coöperates with the higher-level draft bar 27, hereinbefore known as the side-draft bar because its end to which the respective draft animal is to be hitched is to one side

of the path of the other draft animals when 65 hitched to the three-horse evener.

The operation of this device, in general, is as follows:—Assuming that the whiffletrees 50 and 55 and the side-draft bar have each an animal hitched thereto, and each 70 animal exerts power or pull equal to that of each of the other animals:—Under such conditions, the vertical levers 34 and 22 stand medially between the extremities of their movement about their respective pivots. However, if the pull on the lower end of the lever 34 exceeds three-fourths of the total power or pull exerted by the four draft animals,—then the upper end of the lever 34 is moved rearward and swings the 80 pivotally connected end of the inclined lever 40 rearward so as to move the other end of said lever 40 forward. This movement of the lever 40 shifts the lower ends of the lever 22 and arm 15 forward, thereby 85 (through the medium of the link 29 and arm 14) shifting the link 17 and side-draft bar 27 rearward and thus imposing more of the load on the animal hitched to the side-draft bar and relieving the other three animals 90 proportionately.

On the other hand, if the side-draft animal exerts more than one-fourth (its proportion) of the pull,—this excess pull on the side-draft bar moves the latter forward 95 relative to the frame 10, thereby swinging the lever 34, through the medium of the members 29, 22, 18, 40 and 39, so as to draw the three-horse evener rearward relative to the frame 10 and load thereon. This relative movement relieves the side-draft animal by shifting a portion of the excess of its load to the other three animals, whose proportion of pull is also equalized by the three-horse evener above referred to.

It is to be noted that the member 27 does not act in the capacity of a lever, but that it moves bodily from one horizontal line to another horizontal line parallel with the first said horizontal line. In other words,—the bar 27 is mounted for equal forward movement of both of its ends, and for equal rearward movement of both of its ends.

In Fig. 5, 6 and 7, I have shown a slightly modified form of my invention, wherein means are provided to substitute that form of means shown in the other forms to move the draft bar forwardly and rearwardly. In the present embodiment, I equip the supporting structure 10 with suitable spaced bearings 56 and 57 which support a countershaft 58, as shown in Fig. 5, the latter projecting to each side of the bearings, as clearly shown. Sheave wheels 59 and 60 are keyed to the shaft 58 at suitable points, while flexible cables 61 and 62 are mounted to operate about the wheels or drums, as illustrated in Figs. 6 and 7. The

horizontal side-draft bar 27^a is provided with a lateral extension 63 for connection with one end of the cable 62 as at 64, while a link 65 is mounted on the side-draft bar, for connection with the cable 61.

When the draft on the whiffletree 68 increases, the adjacent end of the side-draft bar 27^a moves forwardly and thereby causes unwinding of the cable 61 and consequent 10 rotation of the counter shaft 58. The rotation of the counter shaft 58 in this manner will, therefore, cause the winding of the cable 62 on the respective drum 60 which will in turn act on the extension 63 of the draft bar to move the latter forwardly, consistent with the other end. Thus it will be noted that the draft bar will be adjusted uniformly at all times. On the other hand, when the draft on the whiffletrees 50 and 55 20 increases, the vertical lever 34 will be rocked so as to move the adjacent end of the draft bar rearwardly thereby increasing the rearward strain on the whiffletree 68. When this operation occurs, the slack of the cable 61 will be taken up by the rotation of the shaft 58 and drum or wheel 59, through the 25 instrumentality of the arm 63 while the cable 62 is being unwound from the wheel or drum 60.

From the foregoing, it is believed that the advantages and novel features of my invention will be readily understood and therefore further detail description is deemed unnecessary.

In reducing my invention to practice, I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claims.

Having thus fully described my invention, what I claim as new and desire to secure by Letters Patent is:—

1. A draft equalizer consisting of a supporting frame, a vertically disposed lever supported on said frame, a lower draft device supported by the lower end of said vertically disposed lever, a second vertically disposed lever which is supported on said frame, an upper draft member horizontally disposed and pivotally connected to the second said lever, means coöperating with said second lever in supporting said horizontally disposed draft member in movable relation to said frame, and a lever inclined to the horizon and operatively connected to the first and second said vertically disposed levers so as to effect relative movement of

said lower draft device and said horizontal draft member.

2. A draft equalizer consisting of a supporting frame, a vertically disposed lever supported on said frame, a lower draft device supported by the lower end of said vertically disposed lever, a second vertically disposed lever which latter is supported on said frame, an upper draft member horizontally disposed and pivotally connected to the second said lever, means coöperating with said second lever in supporting said horizontally disposed draft member in movable relation to said frame, a third lever which latter extends at an angle to the first said lever and is operatively connected thereto, and a link operatively connecting said third lever to said second lever.

3. A draft equalizer consisting of a supporting frame, a vertically disposed lever supported on said frame, a lower draft device supported by the lower end of said vertically disposed lever, a second vertically disposed lever which latter is supported on said frame, an upper draft member horizontally disposed and pivotally connected to the second said lever, means coöperating with said second lever in supporting said horizontally disposed draft member in movable relation to said frame, a third lever which latter extends at an angle to the first said lever and is operatively connected thereto, a link operatively connecting said third lever to said second lever, said link also being operatively connected to said means so as to co-operate therewith and with said second lever in effecting the relative movement of the said upper draft member and supporting frame.

4. A draft equalizer consisting of a supporting frame, a vertically disposed lever supported on said frame, a lower draft device supported by the lower end of said vertically disposed lever, a crank-shaft journaled on said frame and having a depending arm and an up-standing arm, a lever operatively connected to the first said lever and extending at an angle to the length thereof, a horizontally disposed side-draft bar having one end supported by said up-standing arm, a link connecting said depending arm to the second said lever, and movable supporting means connected to said side-draft bar at a point intermediate of its ends.

5. In a draft equalizer, the combination with a supporting frame adapted to be drawn forward, a vertically disposed lever mounted on the front end of said frame and movable in the vertical plane extending from front to rear of said frame, a crank shaft journaled on said frame and having a depending arm and an upstanding arm, an upper draft member pivotally connected to

said up-standing arm, an auxiliary supporting element pivotally connected to one side of said frame and to said upper draft member so as to coöperate with said upstanding arm in supporting one end portion of said upper draft member, a second supporting member which latter is pivotally connected to the other side of said frame and to an intermediate portion of said upper draft member, 5 a lower draft element operatively connected to the lower end of said vertically disposed lever so as to swing the upper end of the latter rearwardly, and means operatively connecting said upper end of the vertical lever with said crank shaft, whereby said upper draft member is moved bodily rearward with relation to said supporting frame in consequence of forward movement of the lower draft member relative to said frame.

10 6. The combination with a frame adapted to be moved forward, of a lower draft member movably connected to the middle front portion of said frame and adapted to be moved backward and forward relative to said frame, a side draft member pivotally connected to opposite sides of said frame in such manner as to be movable forward and backward relative to said frame, a connecting medium whereby the pivotal supports 15 of said upper draft member are limited in their movement relative to one another so that both ends of the upper draft member move equi-distantly, and an actuating medium connecting the lower draft member and the pivotal supports of the upper draft member in such relation that a movement of either of said draft members in one direction effects movement of the other of said draft members in the opposite direction.

20 7. In a draft equalizer, the combination with a supporting frame adapted to be moved forward, of a lever pivotally connected to the front part of said frame and being disposed at an angle to the horizon, 25 a lower draft device operatively connected to one end of said lever and adapted to swing the other end of said lever rearward, a upper draft member pivotally supported on said frame above the first said draft member, a second lever disposed at an angle to the horizon and carried by said frame rearward of the first said lever, a link connecting one end of the first said lever to one end of the second said lever, and a link 30 connecting the second said lever to the pivotal supporting means of the said upper draft member, whereby the movement of said lower draft device in one direction effects movement of said upper draft member in the opposite direction relative to said frame.

8. In a draft equalizer, the combination with a frame adapted to be moved forward, of a lever pivotally mounted to swing in a

plane extending from front to rear of said frame, a multiple-animal draft device mounted on said lever in such relation as to apply the drawing force of several draft animals directly in front of said frame, supporting elements pivotally mounted on opposite sides of said frame, a side draft device movably connected to said supporting elements and thereby supported in a horizontal plane different from the horizontal plane of said multiple-animal draft device and adapted to have an animal hitched to an end thereof, and an actuating medium connecting said lever with said pivotal supporting elements in such manner as to shift said side draft member bodily rearward in consequence of a forward movement of said multiple-animal draft device.

9. In a draft equalizer, the combination with a frame adapted to be moved forward, of a multiple animal draft device movably connected to the middle front portion of said frame so as to be movable forward and rearward, a side draft member having one end portion extending crosswise of the frame and having its other end extending a considerable distance beyond a side of said frame, a plurality of supporting members pivotally connected to said frame and to said side-draft member so as to support the latter in movable relation to said frame, means connecting the pivotal supporting members so that they can move only in unison with one another in the same direction, and a lever operatively connected to said connecting medium and to the said multiple-animal draft device, whereby movement of the latter in one direction effects movement of said side draft member in the opposite direction.

10. In an equalizer, the combination with a frame adapted to be moved forward, a three-horse evener, a vertical lever pivotally connected at one end to said evener and pivotally supported by the front end of said frame, a one-animal draft member, supports pivotally connected to said frame and to said one-animal draft member for supporting the latter in a horizontal position in a plane above said evener, a connecting medium between the pivotal supports of said one-animal draft member, and a lever operatively connected to said connecting medium and to the first said lever in such relation that when the forward pull of the one-animal draft member exceeds one-fourth of the total pull exerted on said evener and draft member, the latter will move bodily forward and thereby cause said evener to move bodily rearward with relation to said frame.

11. In a draft equalizer, the combination with a frame adapted to be drawn forward, a vertical lever pivotally mounted on the front end of said frame, a lower draft de-

vice supported on the lower end of said lever, a draft member horizontally disposed in a plane above said lower draft device, a shaft mounted to turn on said frame, means operatively connecting said upper draft member to said shaft, and means operatively connecting said upper draft member to the upper end of said lever, whereby movement of said lower draft device in the forward

direction causes movement of the upper draft 10 member in the rearward direction.

In testimony whereof I affix my signature in presence of two witnesses.

GEORGE S. DUFFIN.
